(57) **CLAIM**

The ornamental design for an obturator, as shown and described.

DESCRIPTION

FIG. 1 is a front perspective view of an obturator;
FIG. 2 is a front view of the obturator of FIG. 1.
FIG. 3 is a rear view of the obturator of FIG. 1.
FIG. 4 is a left side view of the obturator of FIG. 1.
FIG. 5 is a right side view of the obturator of FIG. 1.
FIG. 6 is a top view of the obturator of FIG. 1; and,
FIG. 7 is a bottom view of the obturator of FIG. 1.
The dashed lines illustrate environment that does not form a
part of the present invention, and no claim is made to the
material illustrated with dashed lines.
The obturator is shown with a symbolic break in its length.
The appearance of any portion of the article between the
break lines forms no part of the claimed design.
